United States Patent

Des. 238,492
Patented Jan. 20, 1976

238,492

CONSOLE FOR A DATA SYSTEM

Richard G. Clayton, Detroit, Mich., assignor to Burroughs
Corporation, Detroit, Mich.

Filed Jan. 28, 1974, Ser. No. 437,025

Term of patent 14 years

Int. Cl. D14—02

U.S. Cl. D26—5 C

FIG. 2.

FIG. 1 is a front perspective view of a console for a data system showing my new design; and

FIG. 2 is a rear perspective view thereof.

I claim:

The ornamental design for a console for a data system, substantially as shown.
